Attest.

UNITED STATES PATENT OFFICE

HARRY G. NORWOOD, OF NEW YORK, N. Y., ASSIGNOR TO THEODORE F. VON DORN, OF NEW YORK, N. Y.

SPRING NUT LOCKING DEVICE FOR RAIL JOINTS

Application filed September 20, 1929. Serial No. 394,065.

This invention relates to a new and novel spring nut locking device, and has been especially designed for use in connection with railway rail joints.

The prime object of the invention is to provide simple, strong, durable, economical, practical and efficient means whereby the meeting ends of the rails will be safely locked and maintained in proper alignment.

10 Further objects of the invention are to so construct an effective locking device from a single piece of high grade spring steel of the desired dimensions that it will securely maintain the locking nuts in locked condition; 15 that it will bind against the securing bolts and retain said bolts in proper transverse alignment, and will serve to prevent any lateral swerving or movement of the meeting ends of the track rails with which it is connected.

20 The foregoing and such other objects as may appear from the ensuing description are accomplished by the construction, location, arrangement, combination and formation of 25 the several parts hereinafter more fully described, illustrated in the accompanying drawings and more particularly pointed out in the claims appended hereto, it being understood that slight changes in the precise shape, 30 proportions and minor details of construction may be resorted to without departing from the spirit or sacrificing any of the advantages of the invention.

In the accompanying drawings forming a 35 part of this specification it will be seen that:

Figure 1 is a side elevation of the improved means embodying my invention shown in connection with a railway rail joint.

Figure 2 is a plan view showing a metallic 40 bar from which the locking device is formed, showing the bar broken away at each end portion thereof.

Figure 3 is an enlarged perspective showing the locking device disconnected from the 45 rail joint.

Figure 4 is a side elevation of the device shown in Fig. 3, and

Figure 5 is a top plan thereof.

In the embodiment of my invention as illustrated, it will be seen that the numeral 1 in-

50 indicates the railway track rails, 2 the rail clamping splice bars, each of said bars being provided with openings therethrough for the reception of a suitable number of securing bolts 3, each bolt being passed through the track rail and the opening formed through the splice bars and securely fitted to the threaded end portion of each bolt is a securing nut 4, said nuts being preferably fitted so as to alternate on opposite sides of the rail 55 joint.

It will be perceived that this invention provides an improved, novel and peculiarly formed locking device formed from a single piece of metal, and preferably made from a 60 heat treated high grade of spring steel such as is usually employed for like purposes, said locking device being stamped or punched out from a bar of metal 5, in a substantially H-shaped formation, thereby reducing the waste 65 of metal to the minimum amount, and so formed as to overlap the meeting ends of the track rails, and is firmly and tightly secured under high spring tension against the outer 70 face of each of the clamping splice bars 2 by the securing bolts and nuts disposed nearest the meeting ends of the track rails, each locking device being stamped or forged by the medium of suitable dies from a single piece 75 of metal folded or doubled upon itself at its central portion 6, and formed with a central longitudinally disposed recess or depression 7, forming an outwardly extended bow-shaped portion 8 at each side thereof throughout its length, and a bolt opening 10 formed 80 therethrough near each of its end portions, as is clearly shown in Figs. 3 and 4.

It will be clearly obvious from this particular formation of the locking device that when it shall have been firmly secured in contact 85 with the rail clamping splice bar 2, by the proper adjustment and tightening of the securing nuts fitted to the bolts, each section of the locking device at the right and left 90 of its vertical center will be under intense 95 spring tension against the inner face of the nut thus forcing the nut under extreme pressure into contact with the threaded portion of the bolt, and at the same time will bind tightly against each bolt, hence when each nut 100

shall have been completely adjusted all accidental turning or loosening of the nuts, usually caused by the excessive jarring that emanates from the rolling stock passing over the joints, will be prevented, and the bolts will be maintained in their proper transverse alinement.

It will also be evident that in the event that a splice bar should be accidentally broken, this type of locking device possessing unusual strength will readily serve to retain the rails in proper alinement until the break is discovered and repaired, thereby preventing what is known as "lipping" of the track rails which is liable to cause a derailment of the rolling stock.

It will be understood that any required or desired number of holes may be formed through the end portions of the track rails and through the splice bars, and that any suitable number of bolts and securing nuts may be employed in the proper locking and securing of the track rail joints.

Having thus described my invention what I claim and desire to secure by Letters Patent is:

1. A spring nut locking device for rail joints, comprising a single piece of spring steel horizontally folded upon itself at its central portion to form two oppositely disposed horizontal members, each of said members being formed with a longitudinally disposed recess in its central inner face extending throughout its length.

2. A spring nut locking device for rail joints formed from a single H-shaped piece of metal, said H-shaped piece being doubled horizontally upon itself at its central portion to form a pair of oppositely disposed horizontal members, each member having a longitudinally disposed recess formed centrally in each inner face throughout its length.

3. A spring nut locking device formed from a single piece of high grade spring steel folded horizontally upon itself at its central portion forming a horizontally disposed member at each opposite side of its central folded portion, each member being provided with a longitudinally centrally and oppositely disposed recess and an outward extension formed in each of its upright portions.

4. A spring nut locking device for rail joints formed from a single H-shaped piece of spring steel horizontally folded centrally upon itself forming a horizontally disposed extension at each side of its central portion, each extension being provided with a longitudinally and centrally disposed recess formed in its inner face at each side thereof, and an outward longitudinal extension formed at each opposite side thereof extending throughout its length.

5. A spring nut locking device for rail

joints, comprising a single piece of high grade spring steel horizontally folded centrally upon itself to form an oppositely disposed horizontal member at each side of its central portion, a longitudinally and centrally disposed recess formed in the inner face of each of said members, a longitudinal outwardly and centrally disposed extension formed on each outer side, and a bolt opening formed therethrough near each of its outer ends.
